UNITARY TUBULAR ELECTRICAL CONTACT
AND WIRING TERMINAL THEREFORArthur C. Peters, Midlothian, Ill., assignor to
Cinch Manufacturing Corporation, Chicago, Ill.,
a corporation of Illinois

Application January 17, 1950, Serial No. 138,946

3 Claims. (Cl. 339—220)

1

The present invention relates to improvements in tubular electrical contacts or terminals, and aim generally to improve existing contacts and terminals of that type.

Heretofore, tubular electrical terminals or contacts have been formed by drawing a continuous walled tubular stem from a flat sheet, and have been provided with an outwardly extending annular bead adjacent one end providing a support-engaging shoulder for abutting engagement with a face of an insulating support when the terminal is attached thereto. Such prior terminals consist of a relatively long tubular contacting prong on one side of the bead and a relatively short attaching portion, in the nature of a tubular eyelet, on the other side of the bead. Attachment of such terminals to the insulating support has been effected by upsetting the end of the tubular body adjacent the bead outwardly over the insulating support.

With such prior tubular contacts electrical connection with the connected conductors has been effected in either of two manners: (1) by inserting the conductor core into the tubular contact from the attaching eyelet end and soldering the core to the contact end of the terminal, or (2) by attaching a separate soldering lug to the attaching eyelet portion of the terminal and soldering the conductor to such lug. In order to secure good electrical conduction the soldering lug is usually soldered to the tubular terminal in addition to being embraced by the upset eyelet attaching portion.

In the first of the above described cases the direct electrical connection of the conductor to the terminal is desirable but in soldering the conductor core to the contact end of the tubular terminal a certain amount of solder frequently adheres to the contact end of the tubular terminal providing a small ball which frequently presents contacting difficulties when the tubular terminal is inserted in its mating socket part. In the second of the above described prior installations, irregularities in the contact end of the terminal are eliminated, but the connection is more costly and requires more space than the first described installation.

The present invention aims to improve existing tubular terminals of the above described types by providing a unitary structure having an

2

elongated tubular contact portion, an intermediate attaching portion adapted to engage opposite faces of a support and an integral soldering terminal portion remote from the contact portion.

More particularly, the invention aims to provide an improved tubular contact or terminal that may be readily and economically rolled from a preformed strip of sheet metal stock and provided with a separate integral contacting portion and an apertured soldering terminal portion.

The above and other objects of the invention will be more readily understood by persons skilled in the art to which the invention relates from a consideration of the accompanying drawings and annexed specification illustrating and describing a preferred embodiment of the invention.

In the drawings:

Fig. 1 is an enlarged side elevation of my improved unitary tubular contact and wiring terminal as applied to an insulated support;

Fig. 2 is a side elevation of the installation illustrated in Fig. 1 as viewed at right angles to Fig. 1;

Fig. 3 is a top plan view of my improved tubular terminal as applied to a support;

Fig. 4 is a greatly enlarged vertical sectional view as taken on the line 4—4 of Fig. 1;

Fig. 5 is a side elevation of the improved unitary tubular contact and wiring terminal prior to attachment to a support;

Fig. 6 is a fragmentary plan view of a strip of fabricated sheet metal stock from which the contact of Fig. 6 is formed; and

Fig. 7 is an edge elevation of the strip of stock shown in Fig. 6.

Referring to the drawings, the combined tubular contact and wiring terminal comprises a tubular sleeve 10 formed from a single piece of sheet metal stock and shaped to provide an elongated cylindrical contact portion 11 extending longitudinally from one end thereof, a cylindrical wiring terminal portion 12 adjacent an opposite end thereof, and an intermediate attaching portion 13.

The elongated contact portion 11 preferably is of cylindrical shape and of uniform cross section throughout its length and is provided with a longitudinal butt edge seam 14 as a result of rolling the tubular contact around a mandrel

(not shown) as hereinafter described. One end of the metal bank, from which the contact is formed, may be slightly bevelled as at 15 along opposite sides to permit curling the end of the tubular contact portion 10 inwardly to provide a rounded apertured nose end 16 facilitating insertion of the contact portion 10 in its cooperating mating socket part, as will be understood by those skilled in the art.

The intermediate attaching portion 13 comprises an outwardly extending circumferential bead 18 in the sleeve 10 at the inner end of the contact portion 11 and spaced from the rounded nose end 16 a predetermined distance according to the depth of the socket portion of the cooperating mating part with which the contact is to be used. This bead provides shoulder or stop means adapted to engage one face of an apertured support S and limit movement of the contact in one direction relative thereto.

This intermediate attaching portion 13 of the contact also includes radially extendable wall sections of the sleeve 10 spaced from the bead 18 and adapted to be displaced outwardly for engagement with the upper face of the support S to securely attach the tubular contact to the support.

As herein illustrated, the outwardly extendable portions of the attaching portion 13 comprise weakened wall sections 20 of the sleeve 10 above the bead 13 as formed by circumferentially disposed apertures 21. These apertures 21 are preferably substantially round holes and the intervening wall sections 20 have concaved side edges, the weakest section of which is in the plane passed through the centers of the aperture 21. Thus, when opposite ends of the sleeve 10 are subjected to end pressure the weakened wall sections 20 will be collapsed or folded outwardly providing tabs 22 adapted to engage and grip the upper face of the support S, as shown in Figs. 1 to 4.

The end portion 12 of the sleeve 10, opposite the contact portion 11 and beyond the attaching portion 13, provides a cylindrical wiring and soldering terminal for the conductor to be electrically connected to the tubular contact. Preferably the side walls of the sleeve 10 are provided with opposed conductor-receiving apertures 24 through which a conductor core C may be looped for attachment to the wiring terminal portion of the sleeve. Preferably the core C is soldered to the terminal for good electrical conduction and such solder connection 25 may either be disposed on the outside or within the sleeve 10 as desired.

To prevent collapsing the wall sections of the wiring terminal portion 12 during the application of end pressure to upset the wall sections 20 of the attaching portion 13, the conductor-receiving openings 24 are of less circumferential dimension than the openings 21 so that the intervening wall sections 25 of the wiring terminal portion 12 are stronger and offer greater resistance to deformation under end pressure than the wall section 20. Preferably, the apertures 24 are elongated and are spaced apart a greater distance than the apertures 21.

The improved combined tubular contact and wiring terminal is advantageously formed by rolling or otherwise shaping a blank of metal cut from a prefabricated strip as shown in Figs. 6 and 7. Such a prefabricated metal strip may be formed with a V-shaped bead 18 and punched to provide the spaced apertures 21 of the attaching portion and the conductor-receiving apertures 24. A blank cut from said strip may be shaped around

a mandrel (not shown) into sleeve form as illustrated in Fig. 5.

The improved tubular terminal of the present invention provides a unitary one-piece tubular contact which may be shaped to predetermined length and cross section combined with an intermediate attaching portion and an integral tubular wiring soldering terminal. Inasmuch as the contact and wiring terminal portions are of unitary one-piece construction maximum conduction of electrical current to the contact is provided, and any danger in the shape or cross sectional dimensions of the contact, due to accumulations of solder, is avoided. As will be apparent, the improved terminal may be applied to a support S as readily as the prior terminals first above described.

While I have illustrated and described a preferred embodiment of the invention I do not intend to be restricted to the details thereof as the scope of the invention is best defined in the appended claims.

I claim:

1. A tubular electrical contact and wiring terminal comprising a sheet metal cylindrical sleeve having one longitudinal split extending from end to end thereof and provided intermediate its ends with an outwardly extending circumferential bead defining on one side thereof a tubular contact portion of predetermined length, said sleeve being provided with circumferentially spaced apertures adjacent to and spaced from said bead in a first zone on the side thereof opposite said contact portion and providing therebetween wall sections bucklable radially outwardly under longitudinal load, and said sleeve being extended beyond said apertures and bucklable wall sections to provide an integral tubular wiring terminal portion, said terminal portion in a second zone outwardly spaced from said first apertured zone being laterally apertured to provide for passage of a wire transversely therethrough and being stronger at said second apertured zone than said first apertured zone so that said second zone can transmit buckling pressure to said first zone without collapse of said wire receiving apertures.

2. A tubular electrical contact and wiring terminal comprising a sheet metal cylindrical sleeve provided intermediate its ends with an outwardly extending circumferential bead defining on one side thereof a tubular contact portion of predetermined length, said sleeve being provided with circumferentially spaced apertures adjacent to and spaced from said bead on the side thereof opposite said contact portion and providing therebetween wall sections bucklable radially outwardly under longitudinal load, and said sleeve being extended beyond said apertures and bucklable wall sections to provide an integral tubular wiring terminal portion having lateral wire receiving apertures therein and having wall portions intermediate the apertures thereof of greater width and resistance to buckling under longitudinal load than the wall sections of said intermediate attaching portion.

3. A tubular electrical contact and wiring terminal comprising a sheet metal cylindrical sleeve provided intermediate its ends with an outwardly extending circumferential bead defining on one side thereof a tubular contact portion of predetermined length, said sleeve being provided with circumferentially spaced apertures adjacent to and spaced from said bead on the side thereof opposite said contact portion and providing there-

between wall sections bucklable radially outwardly under longitudinal load, and said sleeve being extended beyond said apertures and collapsible wall sections to provide an integral tubular wiring terminal portion provided with opposed conductor-receiving apertures, said conductor-receiving apertures being collectively of less dimension circumferentially of said sleeve than the apertures of said attaching portion whereby said wiring terminal portion has greater resistance to buckling when subjected to end pressure than said attaching portion.
